DESIGN FOR A CABINET SINK

David E. Anderson, Los Angeles, Calif.

Application December 20, 1941, Serial No. 104,769

Term of patent 14 years

To all whom it may concern:

Be it known that I, David E. Anderson, a citizen of the United States, residing at Los Angeles, in the county of Los Angeles and State of California, have invented a new, original, and ornamental Design for a Cabinet Sink, of which the following is a specification, reference being had to the accompanying drawing, forming part thereof.

Fig. 1 is a perspective view of a cabinet sink, showing my new design.

Fig. 2 is a vertical sectional view of the center-line plane of the left hand drawers and bread board looking toward the right end of the cabinet sink.

Fig. 3 is a vertical sectional view on the plane through the drain trap opening shown in Fig. 1 looking toward the left end of the cabinet sink.

I claim:

The ornamental design for a cabinet sink, as shown,

DAVID E. ANDERSON.
